UNITED STATES PATENT OFFICE.

WILLIAM M. DUNCAN, OF ALTON, ILLINOIS.

FURNACE.

Application filed January 9, 1924. Serial No. 685,269.

This invention relates to improvements in furnaces, and more particularly to a furnace provided with heat-radiating blocks arranged in the combustion chamber to form a heat-radiating arch, or ignition arch.

Prior to this invention it has been customary to locate the arch in an approximately horizontal position directly above the fuel, and a curtain wall usually extends upwardly from the inner end of the arch to form part of a vertical passageway for the hot gases passing from the rear of the combustion chamber to the boiler, or other apparatus to be heated.

One of the objects of the present invention is to simplify the construction, and to economize in manufacture and installation thereof, by avoiding the necessity of using the element known as a curtain wall, and at the same time utilizing the arch to form the front wall of the combustion chamber.

Another object is to increase the efficiency of the furnace by exposing a relatively large portion of the boiler to the radiant heat of the fire in the combustion chamber. Heretofore, the horizontal ignition arch has been arranged directly between a portion of the fire and the boiler where it prevents transmission of radiant heat from that portion of the fire to the boiler. According to the present invention, the heat-radiating arch lies at an angle to the grate, and this angle is preferably greater than 45 degrees, so the arch does not prevent free transmission of radiant heat from the fire to a boiler, or other apparatus, directly above the grate.

Another object is to produce a heat-radiating arch which will not be rapidly worn away by the abrasion of the material known as "fly ash" carried by the flame and hot gases rising from the fuel. If the arch is arranged horizontally, in the usual manner, directly above a fuel bed through which a forced draft is projected, fine particles of ashes and the like are forcibly thrown onto the arch, thereby causing a scouring action tending to destroy the highly heated refractory material in the arch. This destructive action is almost entirely eliminated in the arch herein shown, the arch being inclined to permit free escape of the flame and hot gases which are induced toward the rear of

the furnace, so as to move away from the face of the arch, and this face is not exposed to the hot blast of flame and ashes resulting from a draft forced through the fuel.

A further object is to increase the fuel capacity of the furnace, i. e., to provide for rapid combustion of a large volume of fuel in a furnace where intense heat is desired. The ordinary arch transmits its heat to the front portion of the fuel bed, traveling grates being provided with such arches to aid in the ignition of the fuel which enters the front of the combustion chamber. The arch to be hereafter described may be arranged to very effectively transmit heat to the rear as well as to the front of the fuel bed, and owing to this transmission of the heat, a relatively thick bed of fuel can be quickly and thoroughly consumed on the grate. This is especially advantageous in a furnace wherein it is desirable to obtain a large fuel capacity on a traveling grate.

In a heat-radiating arch, the blocks of refractory material are subjected to intense heat and other conditions which result in breakage of the blocks, and if the arch is approximately horizontal, the cracked or broken parts drop freely from the arch and fall onto the fuel. The arch herein disclosed is preferably arranged at such an angle that the broken parts will, in many instances, be retained in the arch structure until it is convenient to replace the broken block.

A further object is to produce an inclined arch wherein each of the refractory blocks is supported independently of the others, so that the lower blocks are not subjected to the weight of the upper blocks, and each block is free to expand and contract independently of the others. This tends to reduce breakage of the blocks and it is accomplished by means of a simple supporting device which will be hereafter described.

With the foregoing and other objects in view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which

come within the scope of the claims hereunto appended.

Fig. I is a vertical section showing portions of a boiler in a furnace embodying the features of this invention.

Fig. II is a detail view, partly in section, showing a row of the blocks and its supporting means.

Fig. III is an enlarged section on the line III—III in Fig. II.

Fig. IV is a section taken approximately on the line IV—IV in Fig. III, with the blocks shown in elevation.

Fig. V is a detail view showing one of the hangers for the blocks at the bottom of the arch.

Fig. VI is a side elevation of the parts shown in Fig. V.

To illustrate the invention I have shown a mechanical stoker comprising an endless traveling chain grate 1 mounted on wheels 2 and 3, the latter being mounted on a power shaft 4 and provided with a sprocket teeth adapted to drive the grate. The fuel-supporting portion of the grate herein shown is approximately horizontal. A fuel hopper 5 is located above the front portion of the grate and provided with a discharge opening 6 for the discharge of fuel onto the grate. The combustion chamber is provided with a bridge wall 7 at the rear of the grate. The tubes 8 form part of a boiler which lies above the grate.

The front wall of the combustion chamber is formed by a combined heat-radiating arch and curtain wall comprising two horizontal rows of blocks A and A' located at the rear of the fuel hopper 5 and separated from the grate to provide for the admission of fuel. The upper portion of the arch is formed by inclined blocks B (Fig. I) arranged in rows which extend upwardly from the blocks A' to form the front wall of the combustion chamber. Each block is made of refractory material and has a heat-radiating face 9 in the combustion chamber, a head 10 outside of the combustion chamber, and oppositely disposed recesses 11 (Figs. III and V) forming a neck between the head and the body of the block.

The arch support comprises pairs of supporting beams 12 (Figs. I and II) arranged horizontally in front of the inclined arch, and hanger ribs 13 between said arch and supporting beams, said hanger ribs being arranged transversely of said beams and inclined to conform to the inclination of the arch. The supporting means also includes upright suspension members 14 depending from the supporting beams 12 and having their lower ends secured to the hanger ribs 13, plates 15 secured to said hanger ribs and extending between the heads of the adjacent blocks in the arch, and pairs of horizontal rods 16 extending through said plates, said

rods being arranged in the oppositely disposed recesses 11 to support the blocks, as shown most clearly in Fig. III.

Each of the inclined blocks B is thus rigidly suspended from a support including an inclined rib 13, and the rigid suspension device has a four-point contact preventing any pivotal movement of the inclined block and securely supporting the block, so that one inclined block does not rest upon another, and each block is free to expand and contract without liability of breaking or cracking the refractory material. Each rigid suspension device with its four-point contact comprises one of the rigid plates 15 secured at its upper margin by means of two bolts 17 (Fig. III), providing two of the contact points, and the rods 16 contact with two points on opposite sides of a block to form the other contact points. The bolts 17 prevent pivotal motion or downward displacement of the plates 15, and the rods 16 prevent displacement of the blocks B. The rods are arranged in pairs, one above the other, so as to constitute upper and lower block-holding elements in contact with two points on each inclined block, thus preventing pivotal motion or downward displacement of the blocks.

The hanger ribs 13 are preferably T-bars, and the plates 15 can be conveniently bolted to the legs of the T-shaped members. The rods 16 are detachably interlocked with the blocks and said rods can be removed from the plates 15 to permit removal of the blocks.

The hanger ribs 13 are extended forwardly at their lower ends (Fig. I) to receive hangers 18 which embrace the heads of the lower blocks A and A', as shown in Figs. I, V and VI.

The supporting device thus consists of a few simple and inexpensive elements combined with each other to securely hold the blocks in their inclined positions.

Attention is now directed to the inclination of the arch which forms the front wall of the combustion chamber and enables the curtain wall to be dispensed with. The heat-radiating face of the arch preferably lies at an angle of more than 45 degrees relative to the grate. This face lies above the grate and it is directly exposed to the radiant heat of the fire. The arch receives heat rays at a right angle to the top of the grate, and it is so arranged that a straight line at a right angle to the heat-radiating face will extend to the rear of the grate. Consequently, the fuel on the rear, as well as the front, of the grate is exposed to the intense heat radiated from the arch, and the furnace has a relatively large fuel capacity and a high degree of efficiency for the combustion of the fuel before it reaches the rear end of the combustion chamber.

Owing to the inclination of the arch it does not materially interfere with the trans-

mission of radiant heat from the fire to the boiler 8 above the grate, and this is an important factor. The flame and hot gases rising from the grate tend to pass upwardly 5 and over the bridge wall 7, so even though a forced draft is projected through the fuel bed, the arch is not exposed to the destructive scouring action of hot ashes and the like passing upwardly with the flame.

10 I claim:

1. A furnace having a combustion chamber provided with a heat-radiating arch inclined to form the front wall of said chamber, said arch comprising blocks of refractory material each having a heat-radiating face in the combustion chamber, a head outside of the combustion chamber and oppositely disposed recesses forming a neck between the head and the body of the block, 15 supporting beams arranged horizontally in front of said inclined arch, hanger ribs between said arch and supporting beams, said hanger ribs being arranged transversely of said beams and inclined to conform to the 20 inclination of said arch, upright suspension members depending from said supporting beams and having their lower ends secured to said ribs, plates secured to said hanger ribs and extending between the heads of adjacent blocks in the arch, and pairs of horizontal rods extending through said plates, 25 said rods being arranged in said oppositely disposed recesses to support said blocks.

2. A furnace having a combustion chamber having an inclined heat-radiating arch comprising blocks of refractory material, each of said blocks having a head outside of the combustion chamber and oppositely dis-

posed recesses forming a neck between the head and body of the block, supporting 40 beams outside of said chamber, plates suspended from said beams and extending between the heads of adjacent blocks in said arch, and pairs of horizontal rods extending through said plates, said horizontal rods 45 being arranged in said oppositely disposed recesses to support the inclined blocks.

3. A furnace having a combustion chamber provided with a heat-radiating arch inclined to form the front wall of said 50 chamber, said arch comprising transverse rows of blocks of refractory material each having a heat-radiating face in the combustion chamber, a head outside of the combustion chamber and oppositely disposed recesses forming a neck between the head and the body of the block, supporting beams arranged horizontally in front of said inclined arch, hanger ribs between said arch and supporting beams, said hanger ribs being arranged transversely of said beams and inclined to conform to the inclination of said 55 arch, upright suspension members depending from said supporting beams and having their lower ends secured to said ribs, block-holding devices extending from said hanger ribs, and members carried by said block-holding devices, said members lying in said oppositely disposed recesses to support said blocks, the last mentioned members being 60 arranged in pairs and each pair of said members being adapted to support a transverse row of blocks.

In testimony that I claim the foregoing I hereunto affix my signature.

WILLIAM M. DUNCAN.
